United States Patent Office.

JAMES TREES, OF GREENSBURG, PENNSYLVANIA.

Letters Patent No. 67,613, dated August 6, 1867.

IMPROVEMENT IN HOSE-NOZZLES.

The Schedule referred to in these Letters Patent and making part of the same.

TO ALL WHOM IT MAY CONCERN:

Be it known that I, JAMES TREES, of Greensburg, in the county of Westmoreland, and State of Pennsylvania, have invented a new and useful Improvement in Hose-Nozzles, of which the following is a full, clear, and exact description, reference being had to the accompanying drawings, which make part of this specification, and in which—

Figure 1 represents a longitudinal central section through my improved nozzle.

Figure 2, a transverse section through the same, at the line x x of fig. 1.

Figure 3, a view of the tip or point of the central cone detached, and

Figure 4 a view of the modified form of the same.

It is the object of my invention to discharge the water from the nozzle in a smooth, solid stream, and to the greatest practicable distance with a given amount of force or pressure, and to this end my invention consists in combining with a pipe or nozzle of uniform taper, a cone placed centrally within the pipe, so as to form an annular water way.

To carry out my invention I make the pipe A in two sections a a' , united by a screw or other proper coupling, and tapering uniformly from the entrance to the exit at an angle of about five degrees. Concentrically within the pipe I place a cone, B', of corresponding taper, commencing with a fine point at the nozzle of the pipe, and running about three-fourths of its length. A more abrupt cone, B, of about one-third the length of cone B', is placed with its base against the other and in the same axial plane, so as to taper to a point at the entrance of the pipe. The cones are sustained in place by slender supports b , which offer but slight obstruction to the current. These supports or braces are secured to the cone and slip into notches in the pipe, as shown in fig. 2. The long cone is divided into two sections b^1 b^2 , united by a socket joint or other proper connection for the purpose of removing or replacing the tip of the cone. Fig. 4 shows a cone of less inclination, which may, under some circumstances, advantageously be substituted for the other.

I have found by experiment that the water issues from a pipe, such as described, in the form of a hollow cone, and that the pressure of the atmosphere tends to compress the stream to fill this hollow, and thus produce a smooth, solid stream.

What I claim as my invention, and desire to secure by Letters Patent, is—

The combination, substantially in the manner described, with a pipe or nozzle of uniform taper, of two cones arranged base to base concentrically within the pipe.

In testimony whereof I have hereunto subscribed my name.

JAMES TREES.
